UNITED STATES PATENT OFFICE.

CARL JENTZ, OF CAP DE LA MADELEINE, QUEBEC, CANADA.

PAPER-PULP-DIGESTER STRAINER.

Application filed April 30, 1923. Serial No. 635,819.

To all whom it may concern:

Be it known that I, CARL JENTZ, a citizen of the United States of America, and a resident of Cap de la Madeleine, county of 5 Champlain, Province of Quebec, Canada, have invented certain new and useful Improvements in Paper-Pulp-Digester Strainers, of which the following is a full and clear specification.

10 The object of this invention is to provide a simple strainer apparatus which may be easily kept clean and which will be effective in holding back the stock from going out with the liquid and gases, as more fully 15 hereinafter set forth.

In the drawing annexed—

Fig. 1 is a sectional view of the top part of a digester with my invention applied thereto;

20 Fig. 2 is a vertical section on the line 2—2 of Fig. 1.

Referring to the drawing annexed by reference-characters, 5 designates a strainer-pipe extending across the neck of the digester, at a point immediately under the usual removable cover-plate 6, this pipe being supported on brackets 7 bolted or otherwise attached to the interior of the digester-neck, these brackets being curved to conform 25 to the cylindrical shape of the ends of the pipe. This pipe is divided midway its length by an imperforate partition 8, thereby forming two distinct straining chambers, the end-walls of the tube being closed. On 30 each half of the strainer-tube, there is provided an upstanding nipple 9 adapted to receive a depending outlet-tube 10 supported on and extending through the cover. Each of these outlet-tubes 10 is connected to a discharge-pipe 11 and in each discharge-pipe is placed a valve 12. The discharge-pipes empty into a common pipe 13. The strainer-tube is provided with numerous 35 perforations to enable the tube to function as a strainer. The nipples 9 may also be perforated.

In operation, one of the valves 12 will always be closed and the other open, thus permitting only one of the strainers to operate 40 at a time. After this one strainer has operated for a suitable length of time, the valve thereof is closed and the other valve is opened, thus putting the other strainer into operation. In this way, one of the 45 strainers will at all times be free to clear

itself of accumulated pulp which tends to clog its perforations, so that at all times during the cooking operation the function of straining will be maintained at a high degree of efficiency.

It will be observed also that when the cover-plate is removed, the discharge-tubes 10 slip out of the nipples 9, thus leaving the strainer in position to be easily removed for cleaning. It will be observed also that I support the strainer-tube on the digester and not on the cover, where it will be practically impossible for the strainer-tube to become detached and fall into the cooking pulp and thus interfere with the blowoff operation in discharging the digester. As a matter of fact, even tho the strainer-tube should by accident fall into the cooking pulp, its shape is such that it would not interfere with the blowoff of the cooked pulp; its shape is such that it may be readily withdrawn through the blowoff discharge-passage after the blowoff is completed, or "hooked out" from the top.

What I claim as new is:

1. In combination with a paper-pulp-digester and its cover, a pair of outlet-pipes extending through the cover and each provided with a valve, and a hollow perforated strainer divided by an imperforate partition 85 to make two strainer-chambers, each strainer-chamber being connected to one of the aforesaid discharge-tubes.

2. In combination with a paper-pulp-digester and its cover, a perforated strainer-tube supported on the digester below the cover and having a central imperforate partition to thereby make two strainer-chambers and also provided with upstanding nipples, and discharge-pipes extending down through the cover and entering said nipples, each of said discharge-pipes being provided with a valve.

3. In combination with a digester and its removable cover, the cover being provided with a valved discharge-pipe, a strainer-chamber removably supported within the neck of the digester upon the walls thereof, said strainer-chamber having an upstanding tube which has a telescopic connection with the discharge-tube on the cover.

In testimony whereof I hereunto affix my signature.

CARL JENTZ.
